[57] CLAIM

The ornamental design for a cradle for a handheld computer, as shown and described.

DESCRIPTION

FIG. 1 is a front perspective view of a cradle for a handheld computer, showing our design;

FIG. 2 is a front view thereof, the view illustrating a perspective wherein the feet of the apparatus are not visible extended beyond the base;

FIG. 3 is a back view thereof, the view illustrating a perspective wherein the feet of the apparatus are not visible extended beyond the base;

FIG. 4 is a right side view thereof, the left side is a mirror image;

FIG. 5 is a top view thereof; and,

FIG. 6 is a bottom view thereof.
